UNITED STATES PATENT OFFICE.

HARRY SHARPE, OF WATERTOWN, MASSACHUSETTS.

INTERLOCKING MULTIPLE BRICK.

Application filed June 7, 1923. Serial No. 643,861.

To all whom it may concern:

Be it known that I, HARRY SHARPE, a citizen of the United States, residing at Watertown, in the county of Middlesex and State of Massachusetts, have invented new and useful Improvements in Interlocking Multiple Bricks, of which the following is a specification.

This invention relates to building blocks, more especially to blocks such as may be formed of concrete or other suitable material, each block being preferably formed to simulate a plurality of bricks or other building units and each block extending preferably across the entire thickness of the wall, the several blocks forming when laid a securely interlocked construction of great strength and rigidity.

It also provides a construction whereby, if desired, the wall may be laid dry and the cement then forced between the blocks through openings in the rear face of the wall.

For a more complete understanding of this invention reference may be had to the accompanying drawings in which—

Figures 1, 2, and 3 are isometric views of certain forms of blocks which are preferably used in combination in building a wall.

Figure 4 is a rear elevation of the form of block shown in Figure 2.

Figure 5 is a section on line 5—5 of Figure 3.

Figure 6 is a view similar to Figure 4, but showing a different face pattern.

Figures 7 and 8 are isometric views showing the wall in different stages of construction.

Figure 9 is a similar isometric view showing a modification.

In its preferred form, three different forms of blocks are used in making the wall as above noted, though any one of these forms may be used alone, if desired, to construct a wall which is not interlocked vertically between the courses. One of these forms of block is shown in Figure 1. It comprises a substantially flat block of a width equal to the thickness of the wall

desired and preferably having its sides formed to simulate a plurality of rectangular building units such as bricks. These are shown at 1 in this figure. It will be noted that both end faces of this block terminate in marginal surface portions 2 and 3 which are in parallel planes offset from

each other lengthwise of the block and these surfaces are joined by a diagonal surface 4 which is cut back from the face 3 as shown at 5 for a purpose which will later appear. The blocks are thicker adjacent their marginal portions as shown at 6 than intermediate thereof forming a depressed portion as at 7, and the edges of the thicker portions are formed to simulate the joints between successive tiers of bricks. The depressed portions 7 serve to receive cement by which the blocks are bonded together as will later appear. Centrally through the block between its top and bottom faces are openings 8 and surrounding the margins of these openings are grooves 9 extending in closed paths therearound and communicating with the back surface of the block through a notch or groove 10. In the preferred construction this block is only a filler block and is not used except in the uppermost and lowermost courses of the wall.

The main blocks are illustrated in Figures 2 and 3 in which it will be noted that they are double the thickness of the block shown in Figure 1 and represent a pair of superposed courses of bricks, a pair of bricks being shown in each course as at 11, breaking joints with each other. The upper and lower portions of the front and rear faces of the blocks are thus staggered horizontally and in opposite directions and the ends of the block assume a stepped formation having faces 12 and 13 in different parallel planes, the faces 12 at each end of the block being in the same plane and the faces 13 also being in the same plane these faces being in reversed relation to the upper and lower surfaces adjacent opposite faces of the wall. These faces are joined by the diagonal faces 14 which are inclined in opposite directions and which are set back from the faces 13 by the portions 15. These blocks are also provided with vertically extended openings 18 therethrough with surrounding marginal grooves 19 and a groove 20 communicating therewith an opening at the rear face of the block.

The block shown in Figure 3 is similar to the block shown in Figure 2 except that the relative directions of offset at the upper and lower course simulating portions are in the opposite direction, the end face 12' appearing in this form of block at the right hand end of the upper course at the front

- face of the block while in the form shown in Figure 2 the corresponding face 12 is in the lower course at the right hand end. Otherwise the blocks 2 and 3 are similar.
- 5 For convenience in referring to these blocks when built into the wall the form shown in Figure 2 may be designated as an A block, the form shown in Figure 3 as the B block, the form shown in Figure 1 as the C block.
- 10 The rear faces of all the blocks may be formed as desired, for example in Figure 4 they are shown as provided with diagonal grooves 30 to furnish a roughened surface to which plaster may adhere, while in Figure 6 they are shown as simulating courses of bricks as at 31 similar to the pattern on the forward face shown in Figures 1, 2, and 3. When the form shown in Figure 6 is used, the block is a double surfaced block 15 and as the notches 20 to the rear face are substantially limited to the joint simulating portion of the block, these may be filled with cement when the blocks are laid and present a completely finished appearance similar to the forward face.
- 20 Referring to Figures 7 and 8, which shows the preferred manner of laying the blocks, it will be seen that a C block is laid, adjacent thereto end to end an A block. The face 25 13 of the A block in the upper tier overlaps the upper face of the C block, as shown, and at the rear face of the wall the face 13 butts against the end face of the C block, a space 35 being left between their abutting end faces at the front and rear of the wall for the reception of cement. C and A blocks are laid in succession in this manner throughout the length of the wall as shown in Figure 7. Next the B blocks are super-
- 30 posed on the C blocks, as shown in Figure 8. The end face 12' of the B block butts against the end face 13 of the A block overlying the C block, the lower course of brick simulating portions being in the same plane 35 as the upper course of the A block, while the faces 13', of the B block overlie the end portions of the A block adjacent to the faces 13, the upper course of brick simulating portions of the B block being above the upper course of the A block. The B blocks are 40 thus placed in the openings between the A blocks and extend over or lap the A blocks at their ends throughout the length of this course. Next a row of A blocks is laid in 45 the spaces between the B blocks, their ends extending over orlapping the ends of the B blocks, and so on until the wall is at the desired height, the B blocks forming the final course. The blocks A and B therefore lie at different elevations the lower 50 brick simulating course of one facing the horizontal continuation of the upper brick simulating course of the other. C blocks are then placed between the final row of 55 B blocks which serve to finish the top of the

wall flush. Of course if it should be so desired, blocks similar to the C blocks but having their end faces inclined oppositely thereto, might be employed in case it were desired to start or finish the wall with B blocks for the last course instead of A blocks.

The wall may be laid up dry, if desired, and give the appearance of bricks with joints therebetween. Cement in the form of grout may then be forced between the blocks through the notches 20 so that when set the wall becomes a monolithic mass. Of course, if desired, the blocks may be laid up in the ordinary manner with mortar or cement. It will be noted that this construction of blocks effects an interlock both laterally of the wall and vertically, each course being bounded with the courses above and below by the interfitting end portions of the various courses.

85 In Figure 9 is shown the manner of using the blocks in which only one form is required, either the A or B blocks. In the embodiment shown B blocks are employed. These are laid in courses, the ends of the blocks interfitting and overlapping in interlocking relation, but it will be noted that each course of blocks is entirely in one plane so that there is no interlock between the superposed courses of blocks. A or even C blocks could be laid in the same way but the C blocks would have little latteral interlock. In Figures 7, 8 and 9, the forward faces of alternate blocks are shown shaded in order that their relative positions may be seen. It should be understood, however, that in practice they are preferably all alike so that no visible demarcations of the individual blocks appear.

90 Having thus described an embodiment of this invention it should be evident that various changes and modifications may be made therein without departing from its spirit or scope as defined by the appended claims.

100 I claim:

1. A block having its faces at its ends presenting step formations, the step formation adjacent to opposite side faces at the same end being reversed, and end faces inclined in reverse directions in the upper and lower portions of the block joining said step formations, said inclined faces being set inwardly from said step formations thus to provide a pair of diagonally arranged projecting portions at each end of said block, said projecting portions at opposite ends being of substantially the same size.

110 2. A wall comprising a plurality of units, each of certain of said units having a portion in the same plane with and mating a portion of an adjacent unit, and a portion in a different plane and lapping past said other unit, the lapping portions being alternately at opposite side faces of the wall.

3. A wall comprising blocks, certain of said blocks being of one-half the vertical thickness of the remaining blocks and having projecting end portions, the projecting portion at one end being adjacent to one side face and the projecting portion at the other end being adjacent to the opposite side face, the remainder of such blocks each having a pair of projecting portions at each 10 end, each of one-half the vertical thickness of the block and the two arranged adjacent to opposite side faces thereof, said full thickness blocks in the wall being arranged end to end, adjacent blocks being at different horizontal levels, the projections of one fitting between the projections of others, and said half thickness blocks filling in the

spaces between non-adjacent blocks on the same horizontal level at the top and bottom of the wall.

4. A wall comprising blocks certain of said blocks being of less vertical thickness than the remaining blocks, said remaining blocks being laid end to end out of horizontal alinement and having their ends formed to interlock with each other, and said thinner blocks being laid between non-adjacent thicker blocks and presenting therewith horizontal upper and lower faces for said wall.

In testimony whereof I have affixed my signature.

HARRY SHARPE.
